MINIATURE INDUCTIVE DEVICES

Theodore L. Craige, Lynbrook, N.Y., assignor to United Transformer Corporation, New York, N.Y., a corporation of New York

Filed July 26, 1957, Ser. No. 674,342

13 Claims. (Cl. 336—83)

The present application is a continuation-in-part of my application Serial No. 539,395, entitled Miniature Inductive Devices, and is assigned to the same assignee as is that application, said application filed October 10, 1955.

The present invention relates generally to miniature and sub-miniature inductive devices, including inductors, reactors and transformers, and to methods of fabricating these.

It is usual in the art of fabricating inductive devices generally, and transformers in particular, to wind one or more coils on a bobbin of insulating material, and to associate the bobbin with a magnetic core fabricated of laminated or powdered magnetic material. The bobbin must possess sufficient mechanical rigidity to remain undeformed when subjected to stresses, such as those created by the windings. In typical miniature and subminiature transformers and inductors, or the like, intended for low voltage applications, as much as 40% of the window of the usual core structure may be occupied by the bobbin itself. In consequence, conventional cores are larger than I have found to be required in the practice of the present invention.

In accordance with the present invention, the coil of an inductive device is pre-wound, in a bobbin or as a self-supporting coil, and after winding is placed in association with a magnetic core and shell structure fabricated of a single thickness of unpowdered magnetic material. The magnetic structure is formed of two or more conjoinable elements which when placed in conjunction provide an annular container for the coil or coils, magnetically coupling the latter, and also provide a rigid but light enclosure for the coil or coils. The magnetic structure must possess sufficient mechanical rigidity to remain undeformed when subjected to normal strains and must be economical of fabrication, if it is to be commercially feasible. Nevertheless, the structure must not constitute a single closed loop or turn electrically, since such a single loop or turn is subject to extremely high eddy current losses. To avoid a construction which is equivalent electrically to a single short circuited turn, a radial slot is provided in the elements forming the magnetic structure. The slot provides an egress for the wires of the coil or coils and if suitably dimensioned assures low losses in the magnetic structure and hence a structure of high magnetic efficiency.

The magnetic material employed may be sheet material, of nickel-iron alloy and such material has been found to provide desirable magnetic properties and the required structural rigidity, and to permit economy of fabrication.

Small inductive devices, such as transformers, are operated frequently with direct current in one or more windings, which tends to saturate the magnetic circuits of the devices. This is normally compensated for by providing an air gap in the magnetic circuit, which is of precisely selected width. In inductive devices according to the present invention, an air gap or its equivalent may be

2

introduced in the magnetic circuit of the device by arranging the two or more elements which together comprise the magnetic circuit with abutting edges in such physical relation that degree of abutment or extent of gap may be adjusted. The relative physical locations of the two elements, and hence the degree of abutment or gap, may be adjusted until optimum operating conditions are attained for a specific application; and thereafter the relative positions may be fixed permanently, as by incorporating the elements within a mass of potting compound.

The provision of an air gap in the magnetic circuit of any miniature or sub-miniature transformer introduces problems of accurate assembly of conjoined parts, because the air gap must be extremely small and yet must be accurately dimensioned and duplicatable. It has been found that butt joints in units having laminated cores lead to unduly low circuit reactance, because the gap is great relative to core size. On the other hand, interleaving of core laminations leads to high saturation effects, and the effective gap sizes are not duplicatable or readily controllable. In general, accordingly, the mechanical problems involved in providing optimum and economically readily duplicatable core gaps in miniature and sub-miniature transformers has been heretofore insoluble. The ease of adjustment of air gaps possible in constructions according to the present invention, on the other hand, leads to optimum designs and to economy of fabrication, and permits higher signal outputs for a given percentage distortion, by a factor of about 50, in a typical case, when compared with transformers having laminated cores and employing either butt joints or interleaved laminations.

More specifically, magnetic structures according to the present invention are preferably fabricated of two or more elements of generally circular cross-section, which may be conjoined on a common axis, and when so conjoined provide internally for inclusion of a pre-wound coil or coils. The circles of juncture of the elements are then represented by abutting surfaces, one or more of which may be an edge of an element. The extent of overlap of the abutting surfaces or the amount of gap can be adjusted, as by slightly relatively displacing the respective elements, and by so doing the effect of an optimum air gap is introduced, since the reluctance of the magnetic circuit provided by the conjoined elements may be varied.

It is, accordingly, a broad object of the present invention to provide an inductive device of low eddy current loss, and having provision for inclusion of a readily adjustable air gap in its magnetic structure for compensating saturation of the magnetic circuit of the device.

It is another object of the present invention to provide miniature annular core structure of a single thickness of magnetic material, provided with a radial slot for reducing eddy current losses.

A further object of the present invention relates to a miniature annular magnetic shell fabricated of a single thickness of laminated magnetic material, which shall provide an enclosure and a support for a coil, and which shall include a radial slot for reducing eddy current losses.

Still a further object of the present invention resides in the provision of an annular magnetic shell structure fabricated of laminated magnetic material, which shall provide an enclosure and a support for a coil which shall include a radial slot for reducing eddy current losses, and which shall provide a readily adjustable air gap in the direction of the lines of magnetic forces generated by current in the coil.

The above and still further objects, features and advantages of the present invention will become apparent upon consideration of the following detailed descrip-

tion of one specific embodiment thereof, especially when taken in conjunction with the accompanying drawings, wherein:

Figure 1 is an external view in perspective of an inductive device according to the invention;

Figure 2 is a view in section taken on line 2—2 of Figure 1;

Figure 3 is a view in section taken on the line 3—3 of Figure 1;

Figure 4 is a view in perspective of one half the device of Figures 1 to 3, inclusive; and

Figures 5 to 10, inclusive, are views in perspective of various modifications of the structure of Figures 1 to 4 inclusive, each view being taken on a cut-away half of a complete device, and showing magnetic circuit structure to the exclusion of coil structure.

Referring now more specifically to Figures 1 to 4 of the accompanying drawings, the reference numeral 1 denotes a hollow core, of generally cylindrical configuration, and having a central radial aperture 2, of circular transverse cross-section, extending therethrough. The core 1 is fabricated of two similar elements 3 and 4, conjoined at abutting edges 5. A radial slot 6 is provided, which extends through the core to the central aperture 2, so that the core constitutes electrically an open loop or single open turn of conductive material. Mounted internally of the hollow core 1 is a cylindrical pre-wound coil 7, the leads 8 of the windings of which can extend internally of the radial aperture 2, via the slot 6, and thence extend outside the confines of the core.

The coil 7 may comprise two or more coupled windings of a miniature transformer, or a single winding of a choke, or reactor. The coils may be wound on or without a bobbin, and may be insulated from the core 1 by a layer of shellac, or the like, 10.

In the structure of Figures 1 to 4, and assuming the windings to be those of a transformer, in particular, the effect of an adjustable air gap may be provided by relatively shifting the axes of the elements 3 and 4 in directions perpendicular to the axes, so as to vary the overlap of the abutting edges 5, or a gap spacer at the point of abutment can provide the desired gap.

In Figure 4 is illustrated, in perspective, the appearance of the core elements of Figures 1 to 3, half of each core element being removed to facilitate visualization. It may be observed that the edges preferably overlap or abut in part only, which results in a narrowing of the magnetic path at the edges 5, and the transfer of some of the magnetic flux from one core element to the other through an air path.

In particular, the radial slot 6 is common to the several disclosed embodiments of the present invention, and is correspondingly identified in the several views.

In the embodiment of any invention illustrated in Figure 5 of the accompanying drawings, the core elements are 12 and 13. Core element 12 consists of the wall 14, of an axial cylindrical aperture 15, and one end closure wall 16, while the core element 13 consists of the outer cylindrical wall 17 of the core together with another end closure wall 18. The open edge 19 of the closure wall 18 abuts against the outer surface of wall 14, adjoining its edge 20. The edge 21 of closure wall 16 abuts against the inner surface of outer wall 17, adjacent its edge 22. Thereby I provide two air gaps 23 and 24 which may be varied by adjusting the axial relation of elements 12 and 13. If desired, paper spacers may be included in the air gap, and attention is invited to radial gap 6.

In the structure of Figure 6, two cylindrical core elements 30 and 31 are employed, which are generally of circular cross-section taken transversely of the common axis of the core elements, and of U-shaped cross-section taken in a plane through a radius and through the axis of the cylinders. The core element 30, comprises, accordingly, a base 32, and inner and outer parallel walls 33

and 34. The core element 31, likewise, comprises a base 35 and inner and outer parallel walls 36 and 37. Radial slot 6 is provided for the core elements 30 and 31, so that these core elements, or either of them, shall not constitute a single closed turn or loop. The region of overlap of wall 36 with wall 33, or of wall 37 with wall 34, at which the walls are in physical contact, may be varied in respect to area of overlap, by axial adjustment of the elements 30 and 31. Thereby, the reluctance of the magnetic structure may be controlled.

In the arrangement of Figure 7, the core is made up of a first cylindrical element 40, of U-shaped cross-section taken in a plane through the axis of the cylinder. The open end of the U is closed by a disc 41. The cylinder and the disc are provided with mating radial slots 6. Effectively adjustable air gaps are provided by sliding the disc over the edges 45 of the cylinder or spacing the disc from the cylinder. Instead of a disc, an annular piece can be employed which fits snugly within the opening of the structure.

It will also be realized that any motion of the disc 41 transversely of the axis of cylinder 40, will uncover a portion of an edge 45 of the outer wall 47 of cylinder 40, but that the diametrically opposite portion will not simultaneously have its gap changed, since the degree of superposition of the disc 41 over the latter portion of the edge is not changed by such motion. Assuming the diameter of the disc to equal the outer diameter of the cylinder, then, any motion of the disc transversely of the axis of the cylinder will serve to increase the reluctance of the magnetic circuit involved.

In the arrangement of Figure 8, an annular core is fabricated of three elements: a central hollow tube 50 of circular cross section, and two similar units 52, 53 forming a surrounding shell 51. Each of the units includes an outer cylindrical wall and an end closure wall 54 extending at right angles to the outer cylindrical wall. The open edges 55 of the closure walls abut against the central hollow cylinder 50 adjacent the ends thereof, while the open edges 56 of the outer walls abut against each other, so that when the elements are assembled they form a closed hollow annulus, within which may be mounted the coil or coils 7.

A radial slot 6 is formed in the annulus, to avoid eddy currents. The reluctance of the magnetic path may be varied by varying the position of the central tube 50 axially, so as to vary the overlap of the open edge 55 of the closure walls 54 on the inner tube 50.

The embodiment of Figure 9 is similar to that of Figure 7, except that the central tube of Figure 7 is replaced by a solid cylinder 60.

The system of Figure 10 is generally similar to that of Figure 7. The edges of the outer wall of Figure 7 are, however, flared outwardly, as at 62, and the inner wall 55 is flared inwardly, as at 63, the cover disc 41 bearing against the flared surfaces. The latter extends parallel with the cover disc, so that contact therewith may be made over the entire flare. Thereby a wider range of variations of reluctance can be accomplished than is feasible in the system of Figure 7, since a wider range of displacement is available to the disc 41.

If desired, a gap spacer may be provided between cover disc 41 and the flanges 62 and 63.

In production of units according to the present invention, the coil is pre-wound, and is either self-supported or wound on a bobbin. The elements of a magnetic shell, according to the invention, are placed about the coil and provide a support and an enclosure therefor. The air-gap is adjusted for proper operation of the device electrically, and the unit then clamped to prevent relative movement of the elements. The unit is then impregnated with epoxy resin, which, when cured, provides a rigid structure.

While I have described and illustrated one specific embodiment of my invention, it will be clear that variations

of the general arrangement and of the details of construction which are specifically illustrated and described may be resorted to without departing from the true spirit and scope of the invention as defined in the appended claims.

What I claim is:

1. An inductive device including a magnetic shell, a coil located internally of said shell, said shell including a first annular member, a second annular member, said members being coaxial and in metallic contacting and abutting relation, and arranged to provide an enclosure for said coil, and a radial slot extending through said members in said shell for reducing eddy current losses, said slot being constructed and arranged so that said shell constitutes an open loop circumferentially, said magnetic shell being fabricated of a single thickness of laminate, unpowdered magnetic material. 15

2. An inductive device including a hollow magnetic shell, said shell including a first annular member, a second member having axial symmetry with said first annular member, said members being coaxial, at least one of said members being hollow and including parallel annular edges defining an opening for said at least one of said members, the other of said members being arranged to constitute a closure extending over said opening in metallic contact therewith throughout, and a radial slot extending through said members so arranged that said shell constitutes an open loop when taken circumferentially, the area of abutment and contact of said closure with said parallel annular edges being adjustable and defining an air gap of selective extent by virtue of the extent of said overlap, said shell being fabricated of magnetic unpowdered laminate material. 25

3. An inductive device including a hollow magnetic shell, said shell including two conjoined members, each of said members having axial symmetry about a common axis and substantially equal diameters, said members when conjoined providing a substantially closed annular enclosure having a cylindrical inner wall, at least one of said members having two circular walls abutting against and metallically contacting the other of said members, and a radial slot extending through said members so arranged that said shell constitutes an open loop circumferentially, the area of abutment and contact of said abutting circular walls being adjustable and defining an air gap of selective extent, said shell being fabricated of magnetic unpowdered laminate material having walls of uniform thickness. 35

4. The combination according to claim 3 wherein said abutting and contacting circular walls are edges. 40

5. The combination according to claim 3 wherein said abutting walls are axially extending walls. 5

6. The combination according to claim 3 wherein one of said members is U-shaped in radial section. 10

7. The combination according to claim 3 wherein one of said members is a disc. 15

8. The combination according to claim 3 wherein both said members are U-shaped in radial section. 20

9. The combination according to claim 3 wherein both said members are U-shaped in radial section and have abutting edges. 25

10. The combination according to claim 3 wherein both said members are U-shaped in radial section and have abutting axially extending walls. 30

11. The combination according to claim 3, wherein each of said members is L-shaped in radial section. 35

12. A miniature inductive device having a hollow, substantially closed annular magnetic shell of unpowdered laminate magnetic material, said shell including a plurality of members conjoinable to form said shell, the areas of metallic conjunction of said members being areas of contact and being adjusted to provide a predetermined air gap, and a radial slot extending through said magnetic shell whereby said shell constitutes an open loop circumferentially. 45

13. An inductive device including a magnetic shell, a coil located internally of said shell, said shell including a first annular member, a second annular member, said members being coaxial and in abutting relation, and arranged to provide an enclosure for said coil, and a radial slot extending through said members in said shell for reducing eddy current losses, said slot being constructed and arranged such that said shell constitutes an open loop circumferentially, said magnetic shell being fabricated of a single thickness of laminate, unpowdered magnetic material, wherein said coil includes leads and wherein in said leads extend through said slot. 50
